UNITED STATES PATENT OFFICE

94,074

DESIGN FOR A CREAM SEPARATOR

Fredrick David Chapman, Evanston, Ill., assignor to Montgomery Ward & Co., Incorporated, Chicago, Ill., a corporation of Illinois

Application October 13, 1934, Serial No. 53,610

Term of patent 7 years

To all whom it may concern:

Be it known that I, Fredrick David Chapman, a citizen of the United States, residing at Evanston, in the county of Cook and State of Illinois, have invented a new, original, and ornamental Design for a Cream Separator, of which the following is a specification, reference being had to the accompanying drawing, forming a part hereof.

In the drawing the figure is a perspective view of a cream separator showing my new design.

I claim:

The ornamental design for a cream separator, as shown.

FREDRICK DAVID CHAPMAN.
